(57) **CLAIM**

The ornamental design for a handheld device for a respiratory monitor, as shown and described.

DESCRIPTION

FIG. 1 is a front perspective view of a handheld device for a respiratory monitor, in accordance with the present invention.

FIG. 2 is a rear perspective view thereof;

FIG. 3 is a right side view thereof;

FIG. 4 is left side view thereof;

FIG. 5 is an angled top perspective view thereof; and,
FIG. 6 is an angled bottom perspective view thereof.

In the drawings, the broken lines are for the purpose of illustrating unclaimed portions of the handheld device for a respiratory monitor which forms no part of the claimed design.

1 Claim, 5 Drawing Sheets
